Fig. 3.

Fig. 4.

Fig. 5.

Fig. 7.

Fig. 6.

FIG. 1 is a perspective view of a combined tooth shade guide and sterilizing tank therefor, the broken line representations of the teeth have been omitted for ease of illustration.

FIG. 2 is a side elevation thereof in a fully assembled condition;

FIG. 3 is an end elevation thereof;

FIG. 4 is a top plan view thereof;

FIG. 5 is a side elevation of the sterilizing tank with the shade guide removed;

FIG. 6 is an end elevation thereof;

FIG. 7 is a top plan view thereof;

FIG. 8 is a side elevation of the shade guide, removed from the sterilizing tank and inverted, it being understood that the broken line representations of teeth are intended to continue throughout the slotted area seen in FIG. 10;

FIG. 9 is a side elevation thereof; and

FIG. 10 is a top plan view thereof.

FIGS. 2-10 are oriented 90° relative to FIG. 1, for convenience in illustration.

The dominant features of the design reside in the portions shown in full lines.

The side and end not shown in FIGS. 2 and 3 are

identical with the side and end shown therein. The side and end not shown in FIGS. 5 and 6 are identical with the side and end shown therein. The side and end not shown in FIGS. 8 and 9 are, except for obvious differences with respect to the broken line representations, identical with the side and end shown therein.

I claim:

The ornamental design for combined tooth shade guide and sterilizing tank therefor, substantially as shown and described.
